UNITED STATES PATENT OFFICE.

FRANK E. MAYBERRY, OF MEDFORD, MASSACHUSETTS, ASSIGNOR, BY DIRECT AND MESNE ASSIGNMENTS, OF FIVE-EIGHTHS TO WATSON M. HOLMES, OF HOOSICK FALLS, NEW YORK, AND GEORGE A. LOWRY, OF CHICAGO, ILLINOIS.

TELEPHONE SYSTEM.

SPECIFICATION forming part of Letters Patent No. 691,281, dated January 14, 1902.

Application filed March 18, 1901. Serial No. 51,668. (No model.)

To all whom it may concern:

Be it known that I, FRANK E. MAYBERRY, of Medford, county of Middlesex, and State of Massachusetts, have invented an Improvement in Telephone Systems, of which the following description, in connection with the accompanying drawings, is a specification, like characters on the drawings representing like parts.

10 The present invention relates to a telephone signaling system and is embodied in a selective signaling system for party-lines or lines each of which contains two or more stations, the object of the invention being so 15 to arrange the signaling devices that the central office can be called from any station on a line without producing a signal at any other station on the same line, while a call from the central office will affect the signaling device at one station only on the line, so that 20 no one of the subscribers who is not wanted will be disturbed.

The invention further relates to means for locking out the telephone instruments at all 25 the stations on a line except the one which has been called or is calling, so that the line can be controlled for one station without interference caused by the attempt of another subscriber on the same line to call up the central office.

30 The invention is embodied in a system in which the signal-controlling and telephone-controlling devices are independent of the signaling devices and telephones, but are adapted to selectively control the same, the ordinary line-circuit conductors, however, being used as part of the signal-controlling circuit. Each signal-controlling device has a special circuit at each instrument and these several circuits are in multiple, so that any number of 35 stations on a line can be equipped.

The controlling devices for the signaling-circuit and the telephone-circuit at each instrument are operated by an electromagnetic system included in the signal-controlling circuit at each station, the said system including a polarized armature or armatures, so that impulses of current in one direction will operate to set the several signal-controlling de-

50 vices in an abnormal position, while an impulse of current in the opposite direction will operate to restore all of the signal-controlling devices to normal. The several controlling devices on a single line are arranged to operate in unison and are so related to each other 55 that a certain number of movements participated in by the controlling devices will place the signaling device at one station in condition to receive a signal and the signaling devices at the other stations on the same line 60 in such condition that no signal can be received, the same operation placing the telephone at the selected station in condition for use and the telephones at the other stations in such condition that they cannot be connected with the line.

In applying the invention, for example, to the ordinary telephone system the signal-controlling device is provided with a circuit-closer adapted when the said device is properly operated to close the signaling-circuit at the selected station, the signaling-circuits at the other stations being left open, so that when the usual signaling-current is switched onto the line from central office it will affect 75 the signal at the selected station only. The same device which operates the traveling circuit-closer may be arranged to prevent the telephone-circuit from being closed, as by means of a mechanical locking device coöperating, for example, with the gravity-hook at each station and preventing the same from rising when the receiver is removed, so that the telephone cannot be connected with the line. In this construction the signal-receiving circuit or bell-circuit at every instrument is open when the parts are in normal position, (so that no signal will be received when a subscriber on the same line calls central,) and in order that a subscriber may be enabled to 80 call central each instrument is provided with a manually-operating device adapted to close the signal-sending circuit and at the same time to leave the telephone-locking device in 85 such condition that the receiver and transmitter circuits can be closed. This may be accomplished in various ways, a simple and practical way of doing it consisting in divid-

ing the signaling-circuit into branches, one of which contains the magneto or other signal-sending device and has a break which is normally closed by a circuit-closer co-operating with the traveling member of the controlling device and a normally open break adapted to be closed by a push-button, such as is commonly used to complete the magneto-circuit, the other branch being the normally open signal-receiving circuit. Any movement of the signal-controlling device, therefore, from its normal position will break the signal-sending circuit, so that it cannot be completed by means of the manually-operating device, the result being that no signal can be sent from any station after the signal-controlling device has begun to operate to select the station called for or to lock out stations on the calling-line. In the central-energy system the lock for the gravity-hook will prevent the sending of a signal after the signal-controlling device has begun to operate, the signal-sending circuit in this case being entirely independent of the signal-receiving circuit, as is common in this system.

A further feature of the invention is embodied in means for automatically sending a single impulse from the special battery over the calling-line in response to the impulse which gives the signal at the central office. This is accompanied by means for preventing the impulse of current from affecting the circuits at the calling-station, so that while the calling subscriber can be properly connected with the line every other subscriber on the same line is locked out without the intervention of the operator at the central office. This renders it unnecessary for the operator to send locking impulses over the calling-line, and the pole-changing switch may advantageously be arranged so that signal-setting impulses will be sent only over the called line, both lines, however, being included in circuit when the switch is reversed to send the restoring impulse.

The invention further relates to certain novel details of construction and arrangement, which will be hereinafter more fully described.

Figure 1 is a diagram view showing four stations on a line and indicating the special source of current which is used to operate the signal-controlling devices, the other central-office connections being omitted. Fig. 2 is a diagram showing one cord-circuit at central office to indicate the manner in which the special source of current may be connected with the line and also the connection with the usual source of alternating currents for sending out signals. Figs. 3, 4, and 5 are views, partly in section and partly in elevation, drawn practically full size to illustrate the mechanical construction of the devices embodying the invention; and Fig. 6, a view, partly in perspective and partly in diagram, to illustrate the circuits and the manner in which the extra circuits for the signal-con-

trolling devices may be connected with existing instruments without interfering with the regular circuits.

Referring to Fig. 1, each signaling device of a series located, respectively, at different stations on the same line is provided with a circuit-controller having terminals a a^2 in the signaling-circuit, the said terminals being normally separated from each other, but adapted to be closed or bridged by a traveling contact member a^3 , the movement of which is controlled from the central office, the said contact member constituting the signal-controlling device. The said traveling members a^3 at the several stations are located at different distances from the switch-terminals a a^2 , and all of them are arranged to be moved in unison a certain distance in response to a single impulse of current sent over the line from a special source of current at the central office, such as the battery A. The circuits for the battery-current at each station (whether grounded or bridged across the line) are entirely independent of the ordinary signaling-circuits and the telephone-circuits and are arranged in multiple with each other, whereby the currents sent out from the battery A will be divided among all the instruments on a given line, so that the number of instruments to which the devices embodying the invention can be applied is practically unlimited.

The traveling members a^3 when standing in their normal positions are set at different distances from the circuit-closers a and a^2 at the different stations, that at one station, for example, requiring two movements to bring it into engagement with the contact-pieces, that at another station requiring three movements, and so on, there being, however, at least two movements required to complete the circuit at any station, the first movement, as will be hereinafter described, being for the purpose of locking out the several stations on the line.

In the drawings the several devices are shown in the positions in which they will be if four impulses of current have been sent over the line to call up station No. 3. It will be seen that at stations Nos. 1 and 2 the traveling member a^3 has gone beyond the contact-pieces a and a^2 , while at station No. 4 it has not reached the said contact-pieces, so that the signaling-circuit is closed at station 3 only. If, therefore, a current is sent out over the line from the source commonly used for signaling—for example, the magneto B, Fig. 2—it will affect only the bell B^2 at station No. 3, since the bell-circuits at all the other stations are open at the contacts a a^2 .

In conjunction with the signal-controlling device proper each station is provided with a telephone-controlling device or means for preventing the telephone from being used at any station except the one which has been selected and the station originating the call.

As herein shown, the said telephone-con-

trolling device consists of a mechanical lock adapted to coöperate with the gravity-hook C, which normally closes the telephone-circuit when the receiver is lifted. As herein shown, the said locking device consists of a disk b, mounted on a shaft b² and provided with a notch b³ on its periphery, the said periphery being so situated as to engage a projection C², which is connected with the gravity-hook in such a way as to prevent the same from rising except when the said projection is in line with the said notch. The said disk may also be utilized to carry the contact-piece a³, above described, and the relative positions of the said contact-piece a³ and notch b³ are such that when the contact-piece a³ stands in position to bridge or connect the terminals a and a² the notch will be in position to permit the hook C to rise. As has been stated, however, when the device is in its normal position the contact-piece a³ is in a position to leave the contact a and a² open, and consequently the notch b³ is not in a position to permit the hook to rise and close the telephone-circuit. In order, therefore, that a calling subscriber may be able to use his telephone, each instrument is provided with means whereby the signal-sending circuit may be completed and the telephone-circuit also completed at the will of the subscriber, assuming that no other station on his line is busy. This may be accomplished in various ways, it being essential only that the subscriber should be provided with means for manually closing the signaling-circuit at his own station and with means whereby the gravity-hook may be free to move to the position to close the telephone-circuit if the station has not been previously locked out.

As herein shown, each locking-disk b is provided with a supplemental notch b⁴, which normally stands in such position as to permit the rising of the gravity-hook, it being obvious, however, that the said gravity-hook cannot rise when the disk is in any position other than its normal position or its selected position. The signal-sending circuit, which includes the magneto, is provided with two breaks, one including the terminals c c², which are normally bridged or connected by a contact member c³, (shown in normal position in Fig. 6,) also carried by the disk b, and the other having the terminals d d², adapted to be closed by a manual operating device, such as a push-button d³. When the instruments are in their normal condition, therefore, the subscriber by pressing the push-button can complete a signaling-circuit and open communication with central office. If, however, the controlling device has been previously moved, the signal - sending circuit will be broken at the terminals c c², so that no signaling impulse can be sent from the station where the devices are thus in abnormal position. At the selected station, however, the signal-sending circuit is closed, so that the

called subscriber may actuate the clearing-out signal.

The movements of the signal-controlling and telephone-controlling devices above described are produced by the movement of armatures under the control of an electromagnetic system located in a special circuit at each station and adapted to receive current from a special independent source at the central office, as the battery. The system is so arranged that impulses of current sent from the said battery A over the several signal-controlling - device circuits, which are arranged in multiple along the line, will produce step-by-step movements of the several signal-controlling devices, each station requiring a number of impulses peculiar to itself to close its signaling-circuit and place the telephone in condition for use. This is accomplished by providing each instrument with two armatures, one of which will respond to a current flowing in one direction, this being connected with a device for stepping up or setting the several signal-controlling devices, and the other of which will respond only to currents which flow in the opposite direction, the said last - named armature coöperating with a device for restoring all the controllers to normal condition. This may be accomplished by polarizing one or both armatures, it being essential, however, to use only one polarized armature, as will be hereinafter described.

A practical mechanical construction is illustrated in Figs. 3, 4, and 5, the said construction including the electromagnets e and f, the former of which will be referred to as the "stepping-up" electromagnet and the latter as the "restoring" electromagnet. The electromagnet e is provided with the armature e², pivoted at e³ and having connected therewith a pawl e⁴, shown as pivoted at e⁵ upon the arm e⁶, to which the said armature is connected, the said pawl having a spring e⁷, adapted to hold the armature normally retracted. The said armature is arranged to respond only to impulses of current in one direction, and the pawl is adapted to act upon a ratchet-wheel b⁵, mounted on the shaft b², the teeth being cut so that each movement of the said armature when attracted will move the said wheel one notch. The shaft b² is also provided with a restoring-spring b⁶, Fig. 4, against the stress of which it is rotated by the pawl e⁴, and at the end of each step the restoring movement is prevented by the action of a pawl, which is connected with the armature f² of the restoring-magnet f. The said armature f² is shown as permanently polarized by the permanent magnet f³, to which it is connected, the polarity being such that it will not respond to impulses of current which are sent in proper direction to step up or set the controlling device. The said armature f² is shown as connected with the pawl f⁴, which is pivotally supported and acted upon by a restoring-spring f⁵, shown as

connected with a member f^6 , carried by the armature f^2 , the said member f^6 being interposed for a purpose to be hereinafter described. The pawl f^4 therefore acts in conjunction with the ratchet-wheel b^5 as a stop to hold the shaft b^2 at the end of each stepping-up movement, and as soon as the said pawl is moved out of contact with the tooth of the ratchet-wheel b^5 the shaft will be restored to its normal position, which is determined by a suitable stop.

The arrangement of the controlling-device circuits is shown in its simplest form in Fig. 1, in which the only central-office connection illustrated is that of the special battery A, which is provided with a pole-changing switch A^2 , which is shown conventionally in this figure and more in detail in Fig. 2, in connection with which it will be hereinafter fully described. Assuming, for example, that the positive pole of the battery is connected with line-wire 1, an impulse of current is sent from terminal 10 at each station over wire 11 to the gravity-hook C and thence through wire 12 to the stepping-up magnet e , from said magnet through wire 13 to the magnet f , through said magnet f to the wire 14, and thence through wire 15 to the terminal 20 and back through line 2 to the negative side of the battery. Assuming the armature f^2 to be so polarized as not to respond to the current in this direction, it is obvious that the armature e^2 alone will be attracted and that the device at each station may be stepped up as many notches as there are impulses of current sent over the line.

The pole-changing switch is normally at an intermediate position, with the battery A disconnected from the line, and as soon as it has been moved a proper number of times it is left standing in normal position, the operator then switching in the signaling-current from the source B by means of the switch or table-key B^3 , Fig. 2, in the ordinary way, the battery A being disconnected until conversation is finished and it is necessary to restore the controlling devices to normal. Upon receiving the clearing-out signal the operator at central office moves the pole-changer in the opposite direction, connecting the positive terminal of the battery A with the line 2 and the negative terminal with the line 1, the circuit at each station then being from terminal 20 through conductor 15, conductor 14, restoring-magnet f , conductor 13, stepping-up magnet e , conductor 12, gravity-hook C, conductor 11, to terminal 10. The current, however, flowing through both magnets in series and in a direction to attract the polarized armature f^2 will attract the said armature at once and in so doing will close a switch comprising the terminals f^7 and f^8 , thus connecting the wire 13^a with the wire 12 and through the gravity-hook C to wire 11 and short-circuiting the stepping-up magnet e , this taking place so quickly that the armature e^2 is not attracted for a length of time sufficient to

cause the pawl e^4 to prevent the return movement of the ratchet-wheel b^5 , which is then released by the pawl f^4 . The said pawl e^4 , as shown, is normally out of engagement with the ratchet-wheel b^5 , and consequently only acts on said wheel when the armature e^2 is attracted.

In the description of the signal-controlling device reference has thus far been mainly made to Fig. 1, where part of the circuits are omitted for the sake of clearness. In Fig. 6, on the other hand, all of the circuits are included and the several mechanical parts of the actual instrument are shown disconnected in order that the circuits may be clearly traced from one to another, the purpose being mainly to indicate how an ordinary wall-telephone may be wired when the controlling device embodying the invention is applied thereto without materially changing the original wiring. Referring to said Fig. 6, the several circuits may be traced as follows: The circuit for the impulses of current used in setting the devices is as follows: wire 11, (which is connected with line-wire 1,) gravity-hook C, wire 12, binding-post 120, wire 121, (from upper part of binding-post,) magnet e , wire 13, magnet f , (the polarized armature of which is not affected by current flowing in this direction,) wire 14 to the point G, where said wire 14 is connected with the return-wire 15, the said return-wire completing the circuit to the binding-post or terminal 20, and thence to line-wire 2. The circuit for the restoring-current starting with terminal 20 passes through wire 15, point G, wire 14, electromagnet f , (in the right direction to attract the armature thereof,) wire 13, electromagnet e , wire 121, binding-post 120, wire 12, gravity-hook C, and wire 11, this circuit, as above explained, being for the first impulse only, the magnet e being short-circuited through the wire 13^a as soon as the armature f^2 is attracted, as indicated in dotted lines. The contact-pieces f^7 (at the end of wire 13^a) and f^8 are then connected, f^8 being connected with wire 121 at binding-post 120. The signal-sending current starting with the field-terminal of the magneto N passes through the wire 15^a, binding-post 120, wire 12, gravity-hook C to the line through wire 11, (a portion of the current being shunted over the bell-circuit, which will be hereinafter traced, and the magnets e and f ,) thence through the drop at central office and returning to the other terminal of the magneto N through the terminal 20, the wire 15, the switch member d^2 , switch member d , (the push-button d^3 being in the dotted-line position,) wire 15^b, the contacts c^2 and c of the normally closed switch, and the wire 15^c. This circuit is also in multiple with the circuits containing the controlling-device electromagnets and the bell-magnets. The bell-circuit for signals from central office passes through the wire 11, gravity-hook C, wire 12, binding-post 120, wire 12^a to the bell-magnet coils, thence

through wire 12^b to binding-post 12^c, wire 12^d to the member *c* of the normally closed switch, (the said switch, however, being open when a signal is coming in on account of the previous movement of the controlling device,) wire 12^e to the members *a* and *a*² of the normally open switch, (which have been previously bridged by the operation of the controlling device from central office,) from member *a*² to wire 12^f, contact *G*, wire 15 to terminal 20. This circuit is also shunted around the bell-magnets through the magnets *e* and *f*, but as they are of high resistance enough current will pass through the bell-magnet to ring properly.

A subscriber in some cases might desire to call up a party on his own line, and after he had notified central to this effect and had removed his receiver a path of comparatively low resistance would be afforded for the stepping-up impulses of current through his own telephone-circuit, which would practically shunt the higher-resistance electromagnets along the line, upon which magnets the stepping-up operation depends. To obviate this difficulty, a special normally open circuit may be employed, starting from a point between the gravity-hook contact and the induction-coil and terminating at the wire 12, the said circuit having terminals adapted to be bridged by a contact member *d*⁴, connected with the switch member *d*², but being insulated from it, the said circuit being herein shown as consisting of the conductor 16, contact-point 16^a, contact-point 16^b, (which contacts are adapted to be bridged by contact member *d*⁴), conductor 16^c to conductor 12. The receiver-circuit is normally closed through a back contact 16^d through switch member *d*² and wire 15, so that after the receiver has been lifted if the push-button *d*³ is pressed in the receiver will be cut out of the circuit at 16^d and the electromagnets *e* and *f* and the bell-magnet included in the circuit in multiple affording the proper amount of resistance to distribute the current throughout the line. The receiver having been removed, the controlling device at the station will be locked by the projection *C*², so that the calling instrument cannot be affected by the impulses of current passing through the electromagnets *e* and *f*. When the bell at the calling instrument rings, it will indicate that the called instrument has been stepped into circuit and signaled.

As best shown in Fig. 5, the instrument can be contained in a comparatively small box or casing which may be secured to the bottom of the magneto-box, the member *C*² in this case being directly formed upon a supplemental arm *C*³, pivoted at *C*⁴ in the casing, and connected with the gravity-hook *C* by means of a rod or link *C*⁵. If desired, moreover, the device can be provided with a visual signal, which will appear when the line is busy, the said signal being herein shown as an arm *D*, having a projection *D*² with the word "Busy"

printed on it, the said word being normally hidden behind the front of the casing, but adapted to appear through an opening *D*³ (dotted lines) when the controlling device has been moved.

As herein shown, the arm *D* is loosely mounted on the shaft *b*² and is provided with a weight *D*⁴, which tends to cause the said arm to tip toward the position shown in Fig. 3. The said arm is normally held in the position shown in Fig. 5, however, by means of a stop *D*⁵ on the disk *b*, which stop supports the arm, as shown, when the disk is in normal position. As soon, however, as the disk is rotated in the direction to step up the controlling device the stop *D*⁵ will move away from the arm *D*, which will then drop and be arrested by a stop *D*⁶ in the casing, the position then being such that the word "Busy" will show. When the disk is restored to normal, the stop *D*⁵ will carry the arm *D* back to the position shown in Fig. 5 and support it in such position.

In order to prevent possible interference which might occur during the interval of time between the signaling of the central office by a subscriber and the manipulation by the operator at central office of the signal-controlling mechanism, it is desirable to provide means for automatically locking out all instruments on a calling-line in response to the act of any subscriber on the said line in sending in a signal to central office. As a practical means for accomplishing this purpose the signal-drops *h*, Fig. 2, of the several lines may be arranged to close a circuit from the special battery *A* out over the calling-line, the said circuit being broken by the insertion of the answering-plug into the answering-jack. Assuming that a subscriber on the line *F*, Fig. 2, has sent in a signal energizing electromagnet *h*² and causing the drop *h* to fall, the said drop *h* will bridge a pair of contacts 30 and 31, connecting together the wires 30^a and 31^a, the former being connected with the line-wire 1 and the latter with the positive pole of the battery *A*, assuming that the stepping-up current goes from the positive pole to the terminal 10, as described in conjunction with Fig. 1. The negative pole of the battery is connected through the wires 31^b 31^c 31^d with a contact-piece 31^e, which is normally in contact with line-wire 2, but adapted to be carried out of contact therewith when the answering-plug is inserted. As soon, therefore, as any subscriber sends in a signal an impulse from the signal-controlling battery will be sent over the line from which the signal comes, causing the signal-controlling devices on the said line to be stepped up one notch, which is sufficient to break all the signal-sending circuits and lock all the telephones. To prevent the said impulse from affecting the instrument from which the call is sent, the push-button *d*³, which must be pressed in while the signal is being produced, is arranged to coact mechanically with the pawl *e*⁴ and hold the same out of engagement with the ratchet-wheel *b*⁵ during the

attraction of the armature e^2 at that station. The normal position of the parts is shown in dotted lines, Fig. 3, the push-button d^3 having connected therewith a stop or projection d^5 , against which the pawl e^4 normally rests out of engagement with the ratchet-wheel, the said pawl, however, tending to slide upward from said projection toward the ratchet-teeth through the action of the spring e^7 when the 5 armature e^2 is attracted. If the push-button d^3 is pressed inward, however, (see dotted lines, Fig. 6,) it will prevent such upward movement of the pawl until said pawl has passed the tooth with which it would naturally engage, so that it will not cause the ratchet-wheel b^5 to rotate. The calling instrument, therefore, is left in normal position, while the others are automatically locked in response to the signaling impulse. Since the stations 10 on any calling-line are thus locked out in response to the signaling impulse, it is not necessary or desirable to send any further impulses over that line, but only over the line with which connection is desired. To this 15 end the pole-changing switch and cord-circuits are so arranged that the manipulation of the switch to send stepping-up impulses connects the battery A only with the cords of the calling-plug, the reverse movement, however, connecting the cords of both-plugs in order to restore the controlling devices on both 20 of the connected lines.

As shown in Fig. 2, the pole-changing switch A^2 has an operating member A^{30} , provided with 25 a handle A^3 , whereby it can be moved in either direction, such movement operating upon contacts A^4 and A^6 or A^8 and A^{10} to connect them, respectively, with the contacts A^5 and A^7 or A^9 and A^{12} . The operating members A^{30} are 30 mounted on a common shaft or rocker and both moved by the handle A^3 , being shown separate merely for the purpose of clearly indicating the circuits. The contacts A^7 and A^9 are connected together by a wire 40 and 35 through a wire 40^a with the positive terminal of battery A. The contacts A^5 and A^{12} are connected together by the wire 31^c and through a wire 50 with the wire 31^b, which leads to the negative side of the battery. The 40 contacts A^4 and A^8 are connected together and both connected through the wire 60 with the tip-wire H^2 of the calling-plug H, and the contacts A^6 and A^{10} are connected together and both connected with the sleeve-wire H' 45 of the calling-plug II. The corresponding wires J' and J^2 of the answering-plug J are connected, respectively, with terminals A^{13} and A^{14} , which are normally in contact with the terminals A^6 and A^4 . Assuming, therefore, 50 the calling-plug II and the answering-plug J to be placed in such position that the wires H' and J' are respectively connected with the main wires 1 of connected lines and the wires J^2 and H^2 , respectively, connected 55 with the main wires 2 of the said lines, if the handle A^3 of the pole-changing switch A^2 is moved to the left, Fig. 2, the contacts A^4 and

A^5 will be connected, the contacts A^6 and A^7 will be connected, and the contacts A^{13} and A^{14} will be separated from the contacts A^6 70 and A^4 . The circuit from the battery A may then be traced as follows: Starting from the positive pole, current will flow through wires 31^a and 40^a to contact A^7 , thence through contact A^6 to the sleeve-wire H' , sleeve of the 75 calling-plug H, line-wire 1, and back through line-wire 2, tip-wire H^2 , wire 60, contact-piece A^4 , contact-piece A^5 , wire 50, wire 31^b to the negative pole of the battery. By separating the contacts A^{13} and A^{14} from the contacts A^6 80 and A^4 the cord-wire J' , which leads to the contact A^{13} , is disconnected from the cord-wire H' , and the cord-wire J^2 , which leads to contact A^{14} , is disconnected from the cord-wire H^2 , so that neither one of the cord-wires 85 of the answering-plug is connected with the battery-terminals, and no impulse is sent over the line which originated the call. To restore the controlling devices, however, it is necessary to send an impulse of current in 90 the opposite direction over both lines, which is accomplished by moving the handle A^3 to the right, thus connecting terminal A^8 with terminal A^9 and terminal A^{10} with terminal A^{12} . Terminals A^{13} and A^{14} are not by this 95 movement disconnected from terminals A^6 and A^4 , (which are permanently connected, respectively, with terminals A^{10} and A^8 ,) so that the cord-wires J^2 and H^2 remain connected and the cord-wires J' and H' also remain connected. The circuit may be traced as follows: Starting from the negative pole of the battery A, the current passes through conductor 31^b, conductor 50, conductor 31^c to contact member A^{12} , contact member A^{10} , wire 105 70 to cord-wire H' , also dividing at the point A^{50} and passing through contact A^6 and contact A^{13} and wire 80 to cord-wire J' ; thence out over both lines and back through cord-wires H^2 and J^2 to contacts A^4 and A^{14} , joining at A^{51} , and thence through contact A^8 to contact A^9 , wire 40, wire 40^a, wire 31^a to the positive pole of the battery. When the pole-changing switch is in its normal position, as shown, and the answering-plug has been 115 placed in the answering-jack, thereby separating contact 31^c from line-wire 1, the battery A has no connection whatever with the line, and the cord-circuits are the same as usual, the wires H' and J' and H^2 and J^2 being 120 connected by the contact members A^6 and A^{13} and A^4 and A^{14} , which are then closed. The usual source of signaling-current B may then be switched onto the line through the calling-plug by means of the table-key B^3 to 125 call up the desired party, his instrument having been previously stepped into circuit. The clearing-out drop and the listening-in key are indicated in this drawing, but need no description, as they have nothing to do with this 130 invention.

It is not intended to limit the invention to the specific construction hereinbefore shown and described, as modifications may obvi-

ously be made without departing from the invention.

I claim—

1. In a signaling system, a device at each station for placing the instrument at said station in condition to receive signals; means for operating said device by current flowing in one direction; a second device for placing the instrument at said station in such condition that no signal can be received; means for operating said second device by current flowing in the opposite direction; a source of current; and means for sending impulses of current from said source to said devices in either direction.

2. In a selective signaling system for a number of stations, a device at each station for controlling the signaling instrument at said station; a multiple circuit for the several devices; a source of current; means for sending current from said source in either direction over said multiple circuit; means whereby current flowing in one direction will place one of the devices in condition to receive signals; and means whereby current flowing in the other direction will place all of the devices in such condition that no signal can be received.

3. In a selective signaling system, a common line connecting a number of stations with a central station; a signaling device at each station; means located at each station for placing the signaling device in abnormal condition in response to current flowing in one direction; means for restoring said signaling device to normal in response to current flowing in the opposite direction; and means located at the central station for sending impulses of current in either direction.

4. In a party-line telephone system, a central office; a telephone-controller located at each station on a given line; a device for signaling central office located at each station; and means located at central office for operating the telephone-controllers at the several stations on the line in response to the operation of the signaling device at any station on the same line.

5. In a party-line telephone system, a telephone-controller located at each station; a signaling device at each station; means for operating the several controllers in response to the operation of any signaling device on the same line; and a device for preventing said operating means from taking effect at the station which has originated the call.

6. In a party-line telephone system, normally open telephone and signaling circuits at each station; a manually-operating device at each station for closing the signaling-circuit; controlling devices at each station to prevent the closure of the telephone and signaling circuits by the subscriber; means located at central office and operated by a signaling-current from any station for operating the several controllers on the line over which said signaling-current comes in, the manually-operating device being arranged to co-

operate with the controller at the station where it is located to prevent the effectual operation of said controller at that station 70 only.

7. In a party-line telephone system, a central office; a signaling-circuit at each station on a given line; means under control of the subscriber at each station for controlling said circuit; a device at each station for placing said means temporarily beyond the control of the subscriber at said station; and means located at the central office for operating said device.

8. In a party-line telephone system, a locking-out device at each station to prevent the use of the instrument; means located at each station for operating said locking-out device; means for sending a signal from any station to central; automatic devices for operating 85 the several locking-out devices along a line in response to a signal sent from any station on said line; and means for preventing the effectual operation of the locking-out device at the station where the call originated. 90

9. In a party-line telephone system, a controlling device at each station adapted to be operated and restored by impulses of current from a source of current located at central office; means for automatically sending an impulse of current from said source to the several stations on a calling-line in response to a signal sent in over said line; means for connecting said calling-line with the line called for; a controller or switch arranged to send 100 impulses of current in one direction to the stations on the called line only, and to send an impulse of current in the opposite direction to the stations of both lines. 95

10. In a party-line telephone system, a controlling device for the circuits at each station adapted to be operated by impulses of current from central office; a source of current; a cord-circuit for connecting two lines; and means for connecting the terminals of said 110 source respectively with the sleeve and tip-wires of the calling-plug only, as set forth.

11. In a party-line telephone system, a controlling device for the circuits at each station adapted to be operated by impulses of current 115 in one direction and to be restored by impulses of current in the opposite direction; a source of current at central office; means for automatically connecting the terminals of said source with the main wires of a line in 120 response to a signal coming in over said line; a cord-circuit; means for disconnecting said source from the main wires of the calling-line in response to the insertion of the answering-plug; a pole-changing switch for connecting 125 the terminals of said source respectively with the wires of the cord-circuit; and means operating in response to the movement of the pole-changing switch in one direction for disconnecting the terminals of said source from 130 the cord-wires leading to the answering-plug.

12. In a party-line telephone system, a controlling device for the circuits at each station, adapted to be operated by impulses of cur-

rent in one direction and to be restored by impulses of current in the other direction; a source of current at central office; a cord-circuit provided with an answering-plug and a 5 calling-plug; a normally open switch; means for operating said switch to connect the terminals of said source respectively with the sleeve and tip wires of the calling-plug only, for sending operating-impulses over the line 10 to be called; and means for operating said switch to connect the terminals of said source respectively with the sleeve and tip wires of both plugs to send a restoring-impulse over both lines.

15 13. In a party-line telephone system, a signaling circuit at each station normally open; a traveling contact member to close said circuit; a source of current at central office to operate said contact member; and a separate 20 source of current at central office for signaling.

14. In a signaling system, a device for placing the instrument at any of the stations on the system in condition to receive signals; 25 means for operating said device by a current flowing over the line in one direction; a second device for placing the instruments in such condition that no signal can be received; means for operating said second device by a 30 current flowing over the line in the opposite direction; a source of current; and means whereby said source of current can be connected with the line to send current in either direction.

35 15. In a telephone signaling system, a signal-controlling device at each instrument; an operating device therefor; a restoring device therefor, said operating and restoring devices being controlled respectively by coöperating 40 magnetic members; and means for reversing the polarity of one magnetic member without reversing that of the other, whereby either of said devices may be operated at will.

16. In a telephone signaling system, a signal-controlling device at each station; an operating device therefor; a restoring device therefor, said operating and restoring devices being controlled respectively by electromagnets and their armatures, the said electromagnets being connected in series and provided respectively with polarized and non-polarized armatures; means for energizing said electromagnets by current flowing in either direction; and means for short-circuiting 55 the electromagnet having the non-polarized armature in response to the attraction of the polarized armature, as set forth.

17. In a telephone signaling system, a signal-controlling device at each station; an operating device therefor consisting of an electromagnet and its armature; a restoring device consisting of a second electromagnet and its armature, one of said armatures being polarized and the other non-polarized; means 60 for reversing the polarity of the electromagnet having the polarized armature; and means operating in response to the attraction of said

polarized armature for preventing the electromagnet having the non-polarized armature from being energized.

70 18. In a telephone signaling system, a line-circuit common to a number of stations connected with a central office; a signaling-circuit bridged across the line at each station; a signal-controlling circuit also bridged 75 across the line at each station; a signal-controlling device located in each signal-controlling circuit; means for operating said signal-controlling device by current flowing in one direction; means for restoring said signal-controlling device by current flowing in the opposite direction; a source of current for operating and restoring said signal-controlling devices; and a pole-changing switch for connecting either terminal of said source to 80 either terminal of the main line, as set forth.

19. In a telephone signaling system, the combination with a plurality of signaling devices each of which is normally incapable of being operated from the central office; of a 90 controller for each signaling device to place said device in condition to be operated, all of said controllers being bridged across the line and adapted to be operated by the same agency, but so arranged that when one signaling device is placed in condition to operate, the others cannot be operated; means for operating said controllers by current flowing in one direction over the line; means for restoring said controllers to normal condition by current flowing in the opposite direction over the line; a source of current for operating said controllers; and means for changing the direction of current over the line from said source, as set forth.

105 20. In a telephone signaling system, the combination with a plurality of signaling devices on a single line; of a controller for each signaling device, the normal condition of the several controllers being such as to prevent 110 a signal from being sent from or received at any instrument; means normally under the control of the subscriber at each instrument for placing said instrument in condition to send in a signal; a locking device for said 115 means beyond the control of the subscriber; means for operating all of said controllers by current sent in one direction over the line from central office, the controllers being so arranged that only one instrument can be 120 placed by its controller in condition to receive a signal at any one time, and said central office operating means also operating the several locking devices; and means for restoring all the controllers to normal condition by 125 current sent in the opposite direction over the line, as set forth.

21. In a telephone system for party-lines, a signal device and controller therefor at each station, the normal condition of which controller is such as to prevent a signal from being received at said station, and a telephone-controller at each station; the normal positions of said controllers at any one station 130

differing from the normal positions thereof in any other; and means located at the central office, independent of the source of energy which operates the signals, for operating both controllers at every station, substantially as described.

22. In a telephone signaling system for party-lines, a signal-controller, the normal condition of which is such that no signal can be received, combined with means under control of the subscriber whereby a signal may be sent to central office, whereby central office may be signaled without producing signals at other stations on the line; a source of current at central office for operating said controller to place the station where it is located in condition to receive a signal; and an independent source of current for signaling, as set forth.

23. In a telephone system, the combination with a number of signaling devices on a single line; of a circuit-controller for the signaling-circuit at each signaling device; means for placing one only of said circuit-controllers in condition to render its signaling-circuit operative, said means operating in response to a predetermined number of impulses of current flowing in one direction; means for placing all of said controllers in condition to render their respective signaling-circuits inoperative, said means operating in response to a single impulse of current in the opposite direction; an independent source of current for operating said controllers; and means for reversing the direction of current from said source when it is connected with the line, as set forth.

24. In a telephone system, the combination with a number of signaling devices on a single line; of means for producing impulses of current in either direction on the line; a circuit-controller at each signaling device; means for placing one only of said circuit-controllers in condition to render its signaling-circuit operative, said means operating in response to a predetermined number of impulses of current flowing in one direction; means for placing all of said controllers in condition to render their respective signaling-circuits inoperative, said means operating in response to an impulse of current in the opposite direction; and a manually-operative device at each station for rendering the signaling-circuit at said station operative preparatory to sending in a call, as set forth.

25. In a telephone signaling system, the combination with a number of signaling instruments on a single line; of means located at central office for producing impulses of current in either direction; a circuit-controller for closing the signaling-circuit at each instrument; means whereby each circuit-controller is adapted to close the circuit in response to a certain number of impulses of current in one direction from the central office differing from the number required to cause a circuit to be closed by any other circuit-con-

troller; a telephone-controller at each station; means for operating said telephone-controller in response to the operation of the signal-controller; and a device for restoring all of said controllers to normal condition in response to an impulse of current sent in the opposite direction from the central office, as set forth.

26. In a telephone signaling system, the combination with a source of current whereby impulses can be sent in either direction over the signal-controlling-device circuit; of a circuit-controller for the signaling-circuit at each station on one line; means for moving a movable member or contact of the circuit-controller at each instrument a predetermined distance in response to an impulse of current from the central office, the contact members being so arranged that a certain number of impulses of current will close the circuit at one instrument but not at any other; a controller for the telephone-circuit at each station, said controller coacting with each signaling-circuit controller to prevent closure of the telephone-circuit at all stations except the one in which the signaling-circuit is closed; and means for restoring the controllers at every station to normal condition in response to an impulse of current in the opposite direction, as set forth.

27. In a telephone signaling system, the combination with an electromagnet and its armature at each station; of a source of current at central office for energizing said electromagnet; a circuit-controller adapted to be operated by the movement of said armature; a spring for restoring said circuit-controller to normal; a retaining-pawl coöperating with the circuit-controller to resist the action of said spring; an electromagnet and armature to operate said pawl, said armature being polarized; and means for reversing the direction of the current from said source at central office, as set forth.

28. In a telephone signaling system, a normally open signaling-circuit at the subscriber's station; a circuit-closer adapted by a predetermined number of movements in one direction to close said signaling-circuit; said circuit-closer being mounted on a rotatable shaft provided with a ratchet-wheel; an operating-pawl coöperating with said ratchet-wheel; an electromagnet the armature of which is connected with said pawl; means whereby said armature is caused to effectively operate said pawl when said electromagnet is energized by current in one direction only; a retaining-pawl; a second electromagnet the armature of which is connected with said retaining-pawl; means whereby said second armature is caused to effectively operate said pawl when said second electromagnet is energized by current in the other direction only; and means located at the central office for energizing said electromagnets by current in either direction.

29. In a telephone signaling system, a sig-

- naling-circuit at each station which must be completed before a signal can be sent from or received at said station; a local operating device under the control of the subscriber at 5 each station for completing said signaling-circuit; an electromagnetic system also adapted to complete said circuit when energized by current flowing in one direction; and to open said circuit when energized by current flowing in the opposite direction; a source of current for energizing said electromagnetic system; and means for sending impulses of current in either direction from said source, as set forth.
- 15 30. In a telephone signaling system, a signaling-circuit at each instrument which must be completed before a signal can be sent from or received at said instrument; a local operating device at each instrument for completing said signaling-circuit; an electromagnetic system also adapted to complete said circuit when energized by current flowing in one direction, and to open said circuit when energized by current flowing in the opposite direction; a source of current for energizing said electromagnetic system; means for sending impulses of current in either direction from said source; and means for preventing the operation of the local operating device at 25 any instrument, said means being operated by the said electromagnetic system, as set forth.
31. In a telephone instrument, the combination with the gravity-hook; of a rotatable locking-disk, the periphery of which is so situated with relation to said hook as to prevent the same from being lifted; a notch in said disk; and means located at the instrument and adapted to be operated from the central 35 office for causing said disk to rotate until said notch is in line with the said gravity-hook.
32. In a telephone instrument, the combination with the gravity-hook; of a rotatable locking-disk, the periphery of which is so situated with relation to said hook as to prevent the same from being lifted; a notch in said disk; means located at the instrument and adapted to be operated from the central 45 office for causing said disk to rotate until said notch is in line with the said gravity-hook; and a restoring device for restoring said disk to its normal position.
33. In a telephone signaling system, the combination with the gravity-hook of each instrument on a single line; of a locking-disk coöperating with said gravity-hook and arranged to lock the same except when said disk is in a predetermined position; and means located at each instrument and adapted to 55 be operated from the central office for operating all of said disks in unison, the disks being so arranged that only one at a time can be placed in unlocking position by said operating means, as set forth.
- 65 34. In a telephone signaling system, the combination with the gravity-hook of each instrument on a single line; of a locking-disk

coöperating with said gravity-hook and arranged to lock the same except when said disk is in one or more predetermined positions; 7c means located at the central office for operating all of said disks in unison, the disks being so arranged that only one at a time can be placed in unlocking position by said operating means; and means also located at each instrument and adapted to be operated from the central office for restoring all of said disks to normal position, as set forth.

35. In a telephone system, the combination with the gravity-hook; of a locking-disk coöperating with said gravity-hook at each station on the line and arranged to lock the said gravity-hook except when said disk is in a predetermined position; a normally open signaling-circuit; a circuit - closer carried by 85 said disk and adapted to close said circuit only when said notch is in said predetermined position; and means located at each instrument and adapted to be operated from the central office for operating all of said disks 90 in unison, the disks being so arranged that only one at a time can be placed in unlocking position.

36. In a telephone system, the combination with the gravity-hook; of a locking-disk coöperating with said gravity-hook at each station on the line and arranged to lock the said gravity-hook except when said disk is in a predetermined position; a normally open signaling - circuit; a circuit - closer carried by 100 said disk and adapted to close said circuit only when said notch is in said predetermined position; means located at each instrument and adapted to be operated from the central office for operating all of said disks in unison, 105 the disks being so arranged that only one at a time can be placed in unlocking position; and means also located at each instrument and adapted to be operated from central office for restoring all of said disks.

37. In a two-conductor telephone system, a normally open telephone-circuit and a normally open signaling-circuit at each instrument; means normally under control of the subscriber for closing both of said circuits; 115 and a controller-circuit bridged across the line at the subscriber's station and a controlling device in said circuit adapted to be operated from central office for placing said subscriber's-circuit-closing means beyond the 120 control of the subscriber.

38. In a telephone system, a normally open telephone-circuit at the subscriber's station; and a controlling-circuit bridged across the line at said station and a controlling device 125 in said circuit adapted to be operated from central office for preventing the closure of said telephone-circuit.

39. In a signaling system, a central office and substation; a normally open signaling-circuit at said substation; a device at said substation adapted when in normal condition to close said signaling-circuit; and means located in a circuit bridged across the line at 130

said substation and adapted to be operated from the central office for placing said device in abnormal condition to prevent the closure of said circuit.

5 40. In a telephone system for party-lines, a signal-sending circuit and a signal-receiving circuit at each station; a circuit-controller located at each instrument and means for operating said controller located at the central office, the said circuit-controller when in normal position closing a switch in the signal-sending circuit and leaving the signal-receiving circuit open; and a second normally open switch in the signal-sending circuit under control of the subscriber.

41. In a telephone system for party-lines, a normally open telephone-circuit at each station; means normally under the control of the subscriber for closing said circuit; a device located at each station and adapted to be operated from central office for placing said means beyond the control of the subscriber; a visual indicator coöperating with said device, and means located at each station and adapted to be operated from central office for restoring the telephone-circuit at each station to normal condition, as set forth.

42. In a telephone system for party-lines, a signaling device at each station; a visual "busy" indicator at each station; and means located at the central office and operating in response to the operation of the signaling device for actuating the indicators at the other stations.

43. In a signaling system, a line-circuit; a central station provided with a source of electrical energy; a plurality of signaling-circuits in multiple with said line-circuit; a controller for each of said signaling-circuits; and an electromagnet to operate each of said controllers, the several electromagnets being connected in a multiple circuit supplied from said source of electrical energy.

44. In a signaling system, a line containing a plurality of stations; a signaling device at each station; an electrically-operated controller for each signaling device; a circuit for each controller bridged across the main conductors of the line; a central station; and a source of current at said central station to supply said circuit, as set forth.

45. In a signaling system for party-line telephones, the combination with the line conductors; of a signaling device at each station bridged across the line; a controller for each signaling device; and an independent circuit for each controller, said circuits being connected in multiple; and a source of current at central office for supplying said circuits.

46. In a party-line telephone system, a signaling-circuit and a telephone-circuit at each station; a controlling device for each of said circuits; and a controlling-device circuit at each station independent of the signaling-cir-

cuit and the telephone-circuit, each of the said three circuits being bridged across the line.

47. In a signaling system, a signal-controlling circuit; a central station provided with a source of electrical energy and means for connecting either terminal of said source with either terminal of said circuit; a plurality of signaling-circuits in multiple with said signal-controlling circuit; an electromagnetic system for each signaling-circuit, the said electromagnetic systems being connected in multiple with said signal-controlling circuit; armatures included in each of said electromagnetic systems; and means for operating the controllers by the movements of said armatures, the setting of said controllers depending upon the action of said armatures in response to impulses of current flowing in one direction from said source, and the restoring of said controllers depending upon the movements of said armatures in response to current flowing in the opposite direction from said source.

48. In a party-line telephone system, the combination with a telephone-circuit and a signaling-circuit each bridged across the line at each station; of controlling devices for said circuits; an electromagnetic system to operate the controlling device at each station, said electromagnetic systems being included in a multiple circuit adapted to receive current from central office; and means located at each station for breaking the telephone-circuit and closing a special circuit through said electromagnetic system and that part of the signaling-circuit which includes the bell-magnet coils, substantially as and for the purpose described.

49. In a party-line telephone system, the combination with a telephone-circuit bridged across the line at each station and adapted to be closed by the gravity-hook when the receiver is taken down, and a signaling-circuit also bridged across the line at each station; of means for controlling said circuits consisting in electromagnetic systems at the several stations, said electromagnetic systems being included in a multiple circuit supplied with current from central office under control of the operator at central; a special normally open circuit at each station including said electromagnetic system and the signaling-circuit in multiple with each other; and means independent of the gravity-hook for closing said special circuit and opening the telephone-circuit.

In testimony whereof I have signed my name to this specification in the presence of two subscribing witnesses.

FRANK E. MAYBERRY.
